LOOM ATTACHMENT

Perry A. Burnett, Algeoed A. Fallis, and Daniel S. Pritchett, Experiment, Ga.

Application May 18, 1933. Serial No. 671,756

5 Claims. (Cl. 139—247)

The present invention relates to an attachment for magazine looms and has for its primary object to provide, in a manner as hereinafter set forth, a device embodying a novel construction, combination and arrangement of parts through the medium of which the ends from the bobbins in the magazine will be kept taut at all times so that when the full bobbin is transferred to the shuttle, the ends will be taut and the shuttle will thread properly without breaking the thread.

Other objects of the invention are to provide an attachment of the aforementioned character which will be simple in construction, strong, durable, highly efficient and reliable in operation, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

25 Figure 1 is a view in front elevation of an attachment in accordance with the present invention.

Figure 2 is a plan view thereof.

Figure 3 is an end elevational view with the roll assembly support omitted.

Figure 4 is a detail view in perspective of the oscillating shaft.

Referring now to the drawings in detail, it will be seen that the embodiment of the invention which has been illustrated comprises an angular supporting bar 1 which is mounted on the magazine (not shown) of the loom, as at 2. The bar 1 has mounted on one end a roll assembly which is designated generally by the reference numeral 3. The roll assembly 3 includes a pair of opposed plates 4 which are secured together in spaced relation to each other in any suitable manner, as at 5. Journaled in the plates 4 and projecting beyond the outermost of said plates is a

45 pair of parallel shafts 6 having felt covered friction rolls 7 fixed on their outwardly projecting portions. Slots 8 are provided for one of the shafts 6 for floatingly mounting one of the rolls 7, the floating roll being yieldingly engaged with 50 the other roll 7 by a spring 9 mounted between the plates 4. Fixed on the shafts 6 between the plates 4 are ratchet wheels 10. The spring 9 rides on the hub portion of one of the ratchet wheels 10.

55 The reference numeral 11 designates a tubular

housing which is secured on the bar 1 through the medium of suitable brackets 12. Mounted for oscillation in the tubular housing 11 is a shaft 13, said shaft projecting beyond the ends of the housing and terminating, at one end, in a crank 60 arm 14 which is yieldingly maintained in engagement with the usual hammer 15 of the loom by a spring 16.

Fixed on the other end portion of the shaft 13 is an arm 17 having mounted on its free end 65 pawls 18 which are operatively engaged with the relatively reversed ratchet wheels 10 for driving the rolls 7 in opposite directions. If desirable, or necessary, suitable dogs may be provided for preventing retrograde rotation of the ratchet 70 wheels 10. The reference numeral 19 designates an angular stop for the arm 17 which is adjustably mounted on the adjacent end portion of the tubular housing 11.

Briefly, the operation of the device is as follows: When the hammer 15 of the loom goes down to force a bobbin into the shuttle, the spring 16 is permitted to actuate the shaft 13 for retracting the pawls 18. It may be well to here mention that the ends from the bobbins in the 80 magazine pass between the rolls 7. When the hammer 15 returns to its inoperative position, the shaft 13 is actuated thereby in the opposite direction against the tension of the spring 16 and the rolls 7 are actuated by the pawls 18 for eliminating the slack from the threads extending from the remainder of the bobbins in the magazine.

It is believed that the many advantages of a loom attachment constructed in accordance with the present invention will be readily understood, 90 and although the preferred embodiment of the invention is as illustrated and described, it is to be understood that changes in the details of construction and in the combination and arrangement of parts may be resorted to which will fall 95 within the scope of the invention as claimed.

What is claimed is:

1. An attachment for eliminating slack in the threads from the bobbins in the magazine of a loom comprising a pair of opposed, coacting rolls 100 for the reception therebetween of the threads, a shaft mounted for oscillation on the loom, resilient means for actuating the shaft in one direction, means operatively connecting the shaft to the loom for actuation by said loom in the opposite direction, an arm on the shaft, relatively reversed ratchet wheels connected with the rolls, and pawls mounted on the arm and operatively engaged with the ratchet wheels for actuating 105 110

said ratchet wheels in opposite directions when the shaft is actuated by the loom.

2. An attachment for eliminating slack in the threads from the bobbins in the magazine of a loom comprising a pair of opposed, coacting rolls for the reception therebetween of the threads, relatively reversed ratchet wheels connected with the rolls, a shaft mounted for oscillation on the loom, a spring operatively connected with the 10 shaft for actuating said shaft in one direction, a crank arm on one end of the shaft engaged with the loom hammer for actuating the shaft in the opposite direction, an arm on the other end portion of the shaft, and pawls mounted on the 15 arm and operatively engaged with the ratchet wheels for actuating said ratchet wheels in opposite directions when the shaft is actuated by the loom hammer.

3. An attachment for eliminating slack in the 20 threads from the bobbins in the magazine of a loom comprising a supporting bar mounted on the loom, a pair of spaced, opposed plates mounted on the supporting bar, a shaft journaled in the plates, another shaft rotatably and floating- 25 ly mounted in the plates, opposed coacting rolls fixed on the shafts for the reception therebetween of the threads, resilient means yieldingly urging the roll on the floating shaft into engagement with the other roll, relatively reversed ratchet wheels fixed on the shafts between the plates, 30 a tubular housing mounted on the rod, a shaft mounted for oscillation in the housing, an arm fixed on one end portion of the third-named shaft, pawls mounted on the arm and operatively engaged with the ratchet wheels for actuating 35 said ratchet wheels in opposite directions, and means for oscillating the third-named shaft.

4. An attachment for eliminating slack in the 40 threads from the bobbins in the magazine of a loom comprising a supporting bar mounted on the loom, a pair of spaced, opposed plates mounted on the supporting bar, a shaft journaled in the plates, another shaft rotatably and floatingly mounted in the plates, opposed coacting rolls fixed 45 on the shafts for the reception therebetween of the threads, resilient means yieldingly urging the roll on the floating shaft into engagement with the other roll, relatively reversed ratchet wheels

fixed on the shafts between the plates, a tubular housing mounted on the rod, a shaft mounted for oscillation in the housing, an arm fixed on one end portion of the third-named shaft, pawls mounted on the arm and operatively engaged with the ratchet wheels for actuating said ratchet wheels in opposite directions, and means for oscillating the third-named shaft, the last-named means comprising a spring operatively connected with the third-named shaft for actuating the same in one direction, and a crank arm on said third-named shaft operatively engaged with the loom hammer for actuation thereby for actuating the third-named shaft in the opposite direction against the tension of the spring.

5. An attachment for eliminating slack in the threads from the bobbins in the magazine of a loom comprising an angular bar mounted on the loom, a pair of spaced, opposed plates mounted on one end portion of the bar, said plates having slots therein, a shaft journaled in the plates, another shaft operable in the slots, coacting rolls fixed on the shafts for the reception therebetween of the threads, resilient means yieldingly urging the second named shaft toward the first named shaft for frictionally engaging the rolls, relatively reversed ratchet wheels fixed on the shafts between the plates, a tubular housing mounted on the rod, a shaft journaled longitudinally in the housing and projecting beyond the ends of 100 said housing, a spring operatively connected with the third-named shaft for actuating same in one direction, a crank arm on one end of the third-named shaft engaged with the loom hammer for actuating said third-named shaft in the opposite direction against the tension of the spring, an arm fixed on the other end portion of the shaft, a stop on the tubular housing engageable with the second named arm for limiting rotation of the third named shaft under impulsion by the spring, and pawls mounted on the second named arm and operatively engaged with the ratchet wheels for actuating said ratchet wheels in opposite directions when the third named shaft is actuated by the loom hammer.
